(57)

The ornamental design for a pair of stabilizer arms for patient interface, as shown and described.

DESCRIPTION

FIG. 1 is a front perspective view of a pair of stabilizer arms for patient interface showing our new design; FIG. 2 is an enlarged front perspective view of the pair of stabilizer arms for patient interface of FIG. 1, in isolation; FIG. 3 is a front view thereof; FIG. 4 is a rear view thereof; FIG. 5 is a top view thereof; FIG. 6 is a bottom view thereof; FIG. 7 is a left side view thereof; FIG. 8 is a right side view thereof; and, FIG. 9 is reverse perspective view thereof. The broken lines in the drawings depict portions of the pair of stabilizer arms for patient interface that form no part of the claimed design.
